WILHELM RIEHM, OF AUGSBURG, GERMANY, ASSIGNOR TO THE FIRM: MASCHINEN-FABRIK AUGSBURG, NUERNBERG, AKTIENGESELLSCHAFT, OF AUGSBURG, GERMANY, A CORPORATION OF GERMANY.

INTERNAL-COMBUSTION ENGINE WITH FUEL INJECTED SIDEWISE.

Application filed April 11, 1925, Serial No. 22,330, and in Germany October 20, 1924.

This invention relates to internal combustion engines, and particularly to internal combustion engines of the Diesel or other self-ignition type.

5 It is an object of this invention to provide in internal combustion engines of the character described a means for intimately mixing the fuel and air fed to the cylinders thereof.

10 Other objects and advantages of this invention will be apparent from the following description when taken in connection with the accompanying drawing.

In the drawing in which like characters 15 of reference designate like parts throughout the several views thereof:—

Fig. 1 is a longitudinal section taken on the plane of the line A B of Fig. 2 through a portion of a cylinder constructed in accordance with this invention; and

20 Fig. 2 is a transverse section through the cylinder taken on a plane immediately above the piston of Fig. 1 and looking downwardly.

25 It is well known that in order to get a good combustion with internal combustion engines working with solid fuel injection, the air necessary for the combustion must be brought into a rotary movement in order

30 to obtain a good mixture with the fuel injected. A more efficacious mixture and therefore a more effective combustion can be obtained by using this invention as set out here which is that in conjunction with the

35 rotary circulation of the air the combustion space in the piston head is formed as an annular groove, further that the piston when in the inner dead centre position nearly touches the cylinder head, with the middle part of the piston head, so that there is scarcely any clearance. The piston on its upper stroke then forces the air from the inner part of the cylinder into the said annular groove, and in doing so, a whirling

40 motion vertical to the circulating motion of the air is obtained.

45 Referring to the drawing, the air inlet valve *a* is provided with a screen or collar *a*¹ in the usual manner, which will give the injected air the rotary motion. The combustion space *b* in the piston head is an annular groove. The middle part of the piston head

50 consists of a flat disc *b*¹, and when the piston is in the inner dead centre position, there is a

minimum amount of clearance between the 55 cylinder head and piston head. Owing to this construction the air above the middle part of the piston is forced into the annular groove when the piston moves upwards, and a whirling or rotating motion vertical to the 60 rotary motion as illustrated by the arrows *c* will be obtained.

By this thorough circulation of the air a good mixture of air and fuel is obtained, the fuel being injected through nozzles *d* fitted 65 sideways, (in the form shown in the drawing the nozzles are arranged diametrically opposite and positioned to discharge tangentially of the combustion chamber) and an excellent combustion is thus obtained. The 70 outer rim of the piston head is recessed at *e* to take the fuel nozzles.

It is thus seen that the air introduced into the combustion chamber is first given a rotary motion about the longitudinal axis of 75 the cylinder. By the movement of the piston as previously described the air is then given a whirling motion transverse to the rotary motion, this rotary motion being continued. The fuel is then injected while 80 the air is thus rotating in a plurality of planes. By this means an intimate mixture of the fuel and air is obtained, thus insuring a proper combustion. It is to be noted that the air is introduced longitudinally 85 into the combustion space of the cylinder while the fuel is injected perpendicularly to the longitudinal axis of the cylinder and tangentially of the combustion space, although other arrangements could 90 obviously be used in accordance with this invention.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended 100 claims.

Having now described my said invention, I declare that what I claim is:

1. In an internal combustion engine of the 105 character described, a cylinder having a cylinder head, a piston operating in said cylinder, an annular groove in the head of said

piston formed intermediate the periphery and the center thereof, the middle part of said piston being in the form of a flat disk, said parts being so constructed that when 5 the piston is in a dead centre position the middle part all but touches the cylinder head thus allowing only a necessary clearance, said parts forming an annular combustion chamber, means for admitting air 10 to the combustion chamber and for imparting a rotary motion thereto, and means for injecting fuel into the air in said combustion chamber while the air is thus in motion.

2. In an internal combustion engine of the 15 character described, the combination of a cylinder having a cylinder head, a piston, said parts being so constructed as to form an annular combustion chamber when the piston is in a dead centre position, an air inlet valve opening longitudinally of the cylinder into said combustion space, means associated with said air inlet valve for imparting a rotary motion to the air, and a fuel injection nozzle positioned to discharge into 20 said combustion space transversely of the cylinder and tangentially of the combustion space.

3. In an internal combustion engine of the 30 character described, the combination of a cylinder having a cylinder head, a piston, an annular groove in the head of said piston formed intermediate the periphery of the piston and the centre thereof and adapted to form with said cylinder head an annular combustion chamber when said piston is in a dead centre position, the middle part of said piston being in the form of a flat disk, and means for admitting air and fuel into said combustion chamber.

40 4. In an internal combustion engine of the character described, the combination of a cylinder having a cylinder head, a piston, an annular groove in the head of said piston formed intermediate the periphery of the 45 piston and the centre thereof and adapted to form with said cylinder head an annular combustion chamber when said piston is in a dead centre position, means for admitting air to said combustion chamber, slots in the 50 outer periphery of the piston head opening into the combustion chamber, and fuel injection nozzles adapted to feed fuel through said slots transversely of the cylinder into said combustion chamber.

55 5. In an internal combustion engine of the character described, the combination of a cylinder having a cylinder head, a piston, said parts forming an annular combustion chamber within the cylinder space when the 60 piston is in a dead centre position, means for admitting combustion air to said combustion chamber, said parts and said means be-

ing so constructed and arranged as to impart to the combustion air a rotary motion and a whirling motion transverse to the rotary motion as the piston moves to said dead centre position, and means for injecting fuel into said combustion chamber while the air is thus in motion.

6. In an internal combustion engine adapted to operate on air and solid fuel injection, the method of mixing said air and fuel which consists in rotating said air and also setting up a whirling movement in said rotating air, and then injecting the fuel into 70 said moving air and imparting motion to said fuel such as to augment the movement of the air.

7. In an internal combustion engine having a cylinder adapted to operate on combustion air and fuel injection and having a combustion space positioned within said cylinder, the method of operation which comprises introducing combustion air into said combustion space and imparting a rotary motion thereto, imparting a whirling motion to said air transverse to said rotary motion while continuing the rotary motion, and injecting fuel into said air while thus in motion in a direction to augment the rotary motion of said air.

8. In an internal combustion engine of the character described, a cylinder, a piston therein, said parts forming a combustion chamber within the cylinder space, means for admitting combustion air into said combustion chamber and for imparting a rotary motion thereto, means for imparting a whirling motion to said air transverse to said rotary motion during the continuation of 100 said rotary motion, and means for injecting fuel into the combustion chamber while said air is thus in motion in a direction to augment the rotary motion of said air.

9. In an internal combustion engine of the character described, a cylinder, a piston, said parts forming an annular combustion chamber within the cylinder space when said piston is in a dead-center position, the central parts of said cylinder and piston forming opposed surfaces lying adjacent each other, means for admitting air into said combustion chamber and for imparting a rotary motion thereto, the parts being so constructed that on the inner stroke of said piston a whirling motion is imparted to said air transverse to said rotary motion in said annular combustion chamber, and means for injecting fuel into said annular combustion chamber while the air is thus in motion.

In testimony whereof I have affixed my signature.

DR. WILHELM RIEHM.
